UNITED STATES PATENT OFFICE

2,677,362

GRINDING DISK RECONDITIONER

Laurel M. Back, San Lorenzo, Calif.

Application February 26, 1951, Serial No. 212,800

4 Claims. (Cl. 125—37)

1

The invention relates to a hand-applied tool for dressing and cleaning the working surface of a rotary grinding disc or the like.

An object of the invention is to provide a tool of the class described having a rotary working head which is adapted to constantly present fully operative working points against an abradant face being treated.

Another object is to provide a tool of the class described having a working head comprising a series of axially spaced toothed disc cutters arranged to be independently rotated by a rotating disc for individually treating the engaged surface thereof.

A further object is to provide a rotary cutter head of the character described having means providing an adjustable frictional drag against a turning of its disc cutters during a working application of the head.

A more specific object is to provide a tool of the character described having its head arranged for its periodic reversed working applications to compensate for its wear and to maintain the full operativeness of the tool.

Yet another object is to provide a tool of the class described having its working head replaceably mounted on the handle of the tool in a particularly simple and effective manner.

The invention possesses other objects and features of advantage, some of which, with the foregoing, will be set forth or be apparent in the following description thereof, and in the accompanying drawings, in which,

Figure 1 is a view transverse to the working face of a grinding disc, and showing a present reconditioning tool operatively applied to it.

Figure 2 is a side elevation of the disc and the applied tool.

Figure 3 is an enlarged fragmentary section taken at the broken line 3—3 in Figure 1.

Figure 4 is a partly sectional elevation of a shaft element of the tool structure.

Figure 5 is an enlarged fragmentary, and partly sectional, view taken generally at the line 5—5 in Figure 2.

Figure 6 is an enlarged fragmentary view showing the working relations of successive teeth of a present head to an engaged treated surface.

Figures 7 and 8 and 9 progressively illustrate forms assumed by the working ends of the tool teeth by reason of the wear thereof by an abrasive disc face being treated.

The working face of a grinding member generally comprises abrasive particles secured to and extending from a backing element, and may

2

become effectively smooth with use by reason of a breaking or wearing away of the working points of its abradant particles and/or a clogging of the depressions between the particles with materials removed from workpieces by the working face, said materials including metal filings or paints or sawdust, etc., which may adherently stick to the working surface of the grinding disc. Accordingly, the present tool 11 has been particularly designed for reconditioning an abrasive working surface by a repointing fracturing of abradant particles which have been worn to present relatively smooth working faces and removing material which has become lodged on and between the particles, the tool being manually applied in a particularly effective manner to restore a treated surface to its full working condition. Also, a present tool is effectively self-sharpening for its constant effectiveness as it is worn by abradant surfaces being treated.

For illustrating its use, a tool 11 embodying my invention is shown as operatively applied to the flat working face 12' of a grinding disc 12 which is mounted on a backing member 13 comprising a flat annulus 13' extending from a hub 13'' which is threadedly mounted on the extremity of a driving arbor 14. As particularly shown, a screw cap 15 is threadedly mounted on the extremity of the arbor 14 extending through an axial opening 12'' of the grinding disc 12 and is provided with a radial outer flange 15' for clamping an adjacent circular inner portion of the disc 12 against a complementary countersunk seat provided by the opposed face of the annulus 13' whereby the working face 12' of the disc extends radially outwardly from the flange 15'. The arbor 14 carrying the grinding head assembly may be provided by either a stationary machine in which the disc is disposed in a fixed horizontal or vertical or angular plane or by a portable grinder which is arranged for working application over a flat surface and may be disposed with its working face 12' facing upwardly for a most convenient application of a present tool 11.

It will now be noted that a tool 11 essentially comprises a cylindrical head assembly 17 providing relatively rotatable elements carried on a tubular shaft 18 which is non-rotatably and removably mounted on a handle member 19 extending radially of the shaft axis, working elements 21 of said head assembly being rotatable by the engagement of working points thereof with a moving surface to be treated. The present working elements 21 are formed of sheet

metal of uniform thickness and requisite hardness, comprise discs uniformly and radially slotted inwardly therearound to provide relatively long teeth 22 separated by generally sector-shaped slots 23 in a star wheel conformation, are axially perforated to rotatably receive the shaft 18, and have central hub portions 24 between their shaft-receiving holes and the bases of their teeth. Rings 25 are engaged in pairs as spacers between the hub portions 24 of the toothed discs 21 in their line on the shaft 18, a pair of like rings 26 is mounted on the shaft 18 outwardly of an element 21 at one end of their line, and a pair of rings 27 and 28 is provided opposite the element 21 at the other end of the line. The various spacing rings 25 are preferably of like size and thickness whereby the discs may be uniformly spaced along the shaft 18 and present like friction faces to each other and to the opposed disc hub, and the rings 26 and 27 and 28 are of like material and conformation.

As particularly illustrated, the aforesaid cutter elements 21 and the rings 25 and 26 and 27 and 28 are secured on the shaft 18 between outwardly turned terminal flanges 29 thereof whereby the discs 21 and the various washers are retained on the shaft 18 to provide the head assembly 17, it being understood that the washers 25 between the toothed elements 21 function as spacers between the latter elements, and that the end washer pairs function generally as spacers between the shaft flanges 29 and the adjacent elements 21. The arrangement is essentially such that mutually independent relative rotations of the spaced elements 21 are permitted upon the application of the teeth of said elements against a rotating disc 12 while the shaft axis is disposed generally radially of the disc, it being understood that points of the working face '12' of a grinding disc 12 at increasing distances from its center move at proportionally increasing circular speeds as the disc is rotated.

Recalling that the cutters and the various rings of the head assembly are held on the shaft 18 between its end flanges 29 to permit a relative rotation of the cutters 21 by their individual engagement with the working face '12' of a grinding disc 12, means are preferably provided for frictionally and independently restraining the cutters to peripheral rotative speeds which are slightly less than that of the grinding disc at their line of tooth engagement therewith, this insuring a more uniform application of the working points of the cutter teeth of their set. As particularly shown, the washer element 28 of the head 16 threadedly mounts a plurality of screws 31 axially thereof and having their heads disposed outwardly of said washer and having their shank extremities simultaneously engageable in complementary sockets 32 provided in the opposed face of the washer 27. Since the element 28 directly engages a shaft flange 29, and the washer element 26 at the other end of the assembly 17 engages the other end flange 29 of the shaft 18, a screwing-in of the screws 31 as thrust elements against the element 27 is arranged to clamp the remaining elements of the assembly 17 together to an adjusted degree to provide a desired degree of resistance to rotation of the toothed discs 21. It will be understood that the opposed washer and disc faces have the same frictional properties, and that the paired use of the spacer rings in the assembly provides for a more uniform distribution of the frictional drag along the line of discs.

It will now be noted that the present handle 19 comprises a flat and generally V-shaped element shaped of a single piece of round rod or heavy wire to provide like sides 34 extending from an open connecting return bend 35, and having end portions 36 thereof turned mutually inwardly at bends 37 for their simultaneous mounting engagement in the bore of the tubular shaft 18 from opposite ends thereof. The handle element is preferably of somewhat resilient material whereby the handle may be sprung open for mounting or dismounting the described unitary head assembly on and between the handle portions 36. When the handle ends 36 are engaged in the tubular shaft 18 they may swing, or be swung, toward each other to forcibly engage the insides of the bend portions 37 with the ends of the shaft 18 for securing said shaft against rotation about said ends; preferably, and as shown, the end flanges 29 of the shaft member 18 are provided with corresponding notches 29' for complementarily receiving the bend portions of the handle sides for insuring a non-rotative mounting of the shaft on the inturned handle portions 36.

Means are preferably provided for non-rotatably and releasably securing the shaft 18 of a head assembly on the handle 19. As particularly shown, a rectangular plate member 38 having an interior rectangular handle-receiving slot 39 across it and equally spaced from parallel edges of the plate, is provided for mounting on the handle and its advancement along the handle toward the shaft-mounting end thereof to wedgedly draw the handle sides 32 together and effect a positive and releasable gripping of the head 17 by the handle. In the present structure, corresponding notches 34' are provided at mutually opposite points of the handle sides 34 for selectively receiving the portions of the plate 38 at the ends of its slot 39 to secure the plate in adjusted operative position on the handle for effecting the required gripping engagement of the shaft 18 by the handle, it being understood that the release of the installed plate 38 may be effected by springing the handle sides toward each other in their plane. It will be noted that, by reason of the extension of the heads of the clutch screws 31 from the element 28, one of the screw-heads is arranged to engage the corresponding handle side 34 at its bend 37 for securing the clutch element 28 against rotation. Also, the obliquity of the shaft-end flanges 29 provides for their wedged engagement within the bores of the element 28 and the element 26 at the other end of the assembly 17 whereby these elements are further restrained against their rotation with the rest of the elements of the head assembly.

It will now be noted that a present tool 11 is arranged for its manual working application against the working face '12' of a rotating grinding disc 12 with the axis of its head assembly extending generally radially of the axis of rotation of the disc, and with its handle 19 making a relatively small angle with the plane of the disc face '12'. Starting with the head 17 applied with appropriate pressure to the disc face '12' immediately adjacent the flange 15' of the disc securing member 15, the head is swung outwardly on the disc face '12' to progressively operate on the same by reason of the engagement of the moving disc face with the toothed wheels 21 for radially operating across the disc face '12'. In the use of the present tool, experience has shown

that it is best applied with the axis of rotation of its head slightly ahead of and parallel to a radius from the axis of rotation of the disc, whereby the line of the handle 19 makes an angle of about four degrees with a radius intersecting the line of engagement of the head 17 with the disc while the latter is in its starting position. With the head applied against a grinding disc 12 in the particularly described location and manner, no tendency to hold the head inwardly is noted as is the case when the tool is applied on or rearwardly through a radial line from the rotational axis of the disc. The applied tool may be dragged under manually applied pressure across a disc face 12' or be applied by repeatedly striking it against said face as it is moved outwardly thereover.

In the use of a present tool 11 in the indicated manner, it has been found that the end faces of the teeth 22 tend to wear at an angle to radial lines thereto, this effect being heightened by the described clutch-controlled drag which is imposed on the cutter discs 21. As a result of the aforesaid circumferential bevelling wear on the tooth ends, a tooth tends to assume the form shown in Figures 6 and 7 and 9 in which the tooth end face lacks an operating point, but operates rather along a line having the circumferential width of the axially thin teeth, and terminating at an acute-angle rear point 41 of the tooth. If, however, the formed acute-angle points 41 of the teeth 22 of a head 17 are subsequently applied in forward relation to the teeth (Fig. 7), the wear on the teeth ends resulting from a working application of the tool head will progressively wear back the points 41 to provide obtuse-angled points 42 (Fig. 8) which travel across the tooth ends to finally become points 41 (Fig. 9).

Since a forwardly-disposed point 41 and a travelling point 42 are operative as narrow chisel points in the depressions of an abradant face 12', the action thereof is distinctly more effective than is a rearwardly disposed point 41 resulting from a sufficiently long application of the tool to a disc face 12'. Accordingly, when the points 41 have been formed at the rear edges of the teeth 22 of a head 17, the tool is preferably manipulated in a manner to present the formed points 41 forwardly for providing the described travelling point 42, the process being repeated for a continued best operative use of the tool. With the present structure which is symmetrical with respect to the plane of the handle, the forward disposal of a formed point 41 may be simply effected by rotating the tool through a half-turn of the handle to reverse the operativeness of the teeth with respect to the working face 12'. Alternatively, and particularly if the handle and head are not parts of a symmetrical structure, the head 17 may be reversely mounted on and between head-gripping handle members corresponding to the inturned ends 36 of the present handle. For providing the described action, a present cutter wheel 21 desirably has sixteen teeth 22 of uniform width circumferentially of the wheel whereby their ends may remain of substantially constant length as a point 42 is progressively provided along them.

From the foregoing description taken in connection with the accompanying drawings, the advantages of the present grinding disc reconditioner will be readily understood by those skilled in the art to which the invention appertains. While I have described the principles of opera-

tion, together with a form of my invention which I now consider to comprise a preferred embodiment thereof, I desire to have it understood that the showing is primarily illustrative, and that such changes and developments may be made, when desired, as fall within the scope of the following claims.

I claim:

1. In a tool for dressing flat abradant surfaces, a tubular shaft member providing outturned flanges at its ends, a head assembly comprising disc cutters and spacing rings rotatably mounted upon the shaft member between its flanges, a planar handle member of V-outline shaped of a length of wire or the like and having its sides tapering from mutually inturned ends engaged in the bore of the shaft member and cooperative with the flanges of the shaft member to secure the member against rotation relative to the handle, and a plate member providing an interior slot slidably receiving the handle transversely therethrough with the handle sides in frictional slidable engagement with the slot ends and with the plate movable along the handle toward the engaged shaft member to wedgedly force the sides of the handle toward each other in their plane to effect a gripping of the engaged shaft flanges against a rotation of the shaft with respect to the handle.
2. In a tool for dressing flat abradant surfaces, a shaft member providing outturned flanges at its ends, a plurality of like disc cutters providing circumferentially spaced teeth and rotatably mounted upon the shaft member between its flanges and arranged for mutually independent rotations thereof by reason of the application of the tooth ends to a moving work surface, spacing rings alternating with the disc cutters on the shaft member in frictional engagement therewith, end pairs of spacing rings engaged between the different flanges of the shaft member and the end cutters of their line, and thrust screws carried by a latter spacing ring and adjustable transversely of the ring and against the opposed spacing ring of its pair to effect an adjusted frictional engagement of the cutters and the spacing rings engaging them.
3. In a tool for dressing flat abradant surfaces, a shaft member providing outturned flanges at its ends, a plurality of like disc cutters providing circumferentially spaced teeth and rotatably mounted upon the shaft member between its flanges and arranged for mutually independent rotations thereof by reason of the application of the tooth ends to a moving work surface, pairs of spacing rings alternating with the disc cutters on the shaft member and including end pairs between the end cutters and the flanges having the outer rings thereof engaging the different flanges of the shaft member and the inner rings engaging mutually opposed cutters, and thrust screws directly coactive between the spacing rings of a said end pair transversely thereof to mutually and forcibly separate said rings for a mutual frictional engagement of the cutters and rings in their line.
4. In a tool for manual manipulation for cleaning and dressing abradant surfaces, a tubular shaft member, a head assembly comprising disc cutters and spacing rings rotatably mounted upon the shaft member between its ends, a planar handle member of V-outline shaped of a length of wire or the like and having its sides tapering from mutually inturned ends engaged in the bore of the shaft member, and a plate

member providing an interior slot slidably receiving the handle transversely therethrough with the mutually outer faces of the handle sides in frictional engagement with the slot ends whereby the plate is movable along the handle toward the handle-mounting shaft from the smaller handle end to force the sides of the handle member toward each other in their plane to effect a non-rotative gripping of the engaged shaft between them.
